BOOKMARKER

Cornelius C. Washburn, Lakeland, Fla.

Application July 11, 1935, Serial No. 30,923

6 Claims. (Cl. 116—119)

My invention relates to an improvement in bookmakers.

In the past, many forms of bookmarking devices have been in use primarily as temporary markers to indicate a page which is later to be easily found. Many markers, such as markers used in card index files, are provided with protruding edges which are adapted to receive a number or some other indicating media, such 5 markers being either permanent or of a type which may be secured to a page or card so that it may be removed at a later date.

In the past, markers for books which are adapted to indicate a page which may be referred 15 to, have been secured within the book by some clamping device closely associated with the binding of the book.

An object of my invention is to provide a bookmarker which is adapted to fit over a page to be 20 marked and leave a portion of the marker protruding beyond the edge of the page so that reference may be readily had to a desired page.

A further object of my invention is to provide a bookmarker which is adapted to be placed over 25 a page so that one strip forming the marker will be on each side of the page.

A further object of my invention is to provide a bookmarker which has portions thereof extending 30 beyond the edge of a page which is to be marked, these portions being secured to the holding portion of the marker in varying positions relative to its length, so that the protruding edges will not overlap one another.

A further object of my invention is to provide 35 a bookmarker having portions thereof extending beyond the edge of the page which is to be marked, these portions being of varying lengths and secured to the holding portion of the marker so that the holding portion will be positioned at 40 varying distances from the binding of the book to which several markers have been applied.

A still further object of my invention is to provide 45 a bookmarker which is telescopic so that one given marker may be adjusted to fit pages of different sizes.

A still further object is to provide a bookmarker 50 which is adapted to hold a sheet of reference paper which may be of water-proof or washable paper so that the memoranda placed on the sheet may be erased or changed from time to time, these memoranda sheets being removably secured to the bookmarker which is positioned on a given page to be marked.

A still further object of my invention is to provide 55 a bookmarker which is adapted to hold, on

the end thereof which protrudes beyond the edge of the page to be marked, a reversible indicating medium, which indicating medium is adapted to have varying marks on the opposite sides thereof.

In the accompanying drawings:

Fig. 1 is a side elevation of one form of my bookmarker in position over a page to be marked;

Fig. 2 is a vertical cross-section on the line 2—2 of Fig. 1;

Fig. 3 is a horizontal cross-section on the line 10 3—3 of Fig. 1;

Fig. 4 is a vertical cross-section on the line 4—4 of Fig. 1;

Fig. 5 is an enlarged fragmentary disassembled view of one form of a protruding end of the 15 marker;

Fig. 6 is a fragmentary plan view of a slightly modified form of the protruding end;

Fig. 7 is a fragmentary plan view of the modified form shown in Fig. 6;

Fig. 8 is a vertical cross-section on the line 8—8 20 of Fig. 6;

Fig. 9 is an enlarged fragmentary disassembled perspective view of the form shown in Fig. 6;

Fig. 10 is a view in side elevation showing a 25 telescopic form of my bookmarker applied to a page;

Fig. 11 is a horizontal cross-section on the line 11—11 of Fig. 10;

Fig. 12 is a horizontal cross-section on the line 30 12—12 of Fig. 10;

Fig. 13 is a vertical cross-section on the line 13—13 of Fig. 10;

Fig. 14 is a perspective view of a modified form 35 of marker shown in Fig. 16;

Fig. 15 is a plan view of the modified form shown in Fig. 16;

Fig. 16 is a side elevation of a modified form of bookmarker attached to a page to be marked, this figure showing several markers of different 40 configuration applied to a single page to be marked;

Fig. 17 is a side elevation of a telescopic form of marker provided with a sheet of memoranda paper;

Fig. 18 is a vertical section on the line 18—18 45 of Fig. 17;

Fig. 19 is a horizontal cross-section on the line 19—19 of Fig. 17;

Fig. 20 is a horizontal cross-section on line 50 20—20 of Fig. 18;

Fig. 21 is a fragmentary end view of a modified form of the marker strips; and

Fig. 22 is a fragmentary perspective view of the modified form shown in Fig. 21.

I provide two relatively thin strips **2** preferably made of celluloid or thick cellophane, which strips are secured together at both ends **4** thereof by any suitable cement, in which case they will assume the position shown in Figs. 1, 10, 16 and 17, or which may be folded over upon themselves at the ends thereof as shown in Figs. 21 and 22. Between the two end portions **4**, the strips **2** are separable so that they may be placed over a page **6** which is to be marked.

Strips **8** of the same material are laterally secured to each of the strips **2** by a suitable cement. These strips **8** extend outwardly from the strips **2**, and the outer ends thereof **10** are cemented together so that when the strips **2** are placed over a page **6**, the page will also be in position between the strips **8** with the portion **10** thereof extending out past the edge of the page. As shown in Fig. 5, the outer end **10** of the strips **8** may be cut away as at **12**, so that the reference indicator **14** may be slipped over the end **10**. This reference indicator **14** may be made of any suitable material, for example in varying colors, and having varying reference numbers or letters on either or both sides thereof.

The strips **8**, as shown in Fig. 1, may be modified slightly to provide the end portion particularly disclosed in Figs. 6, 7, 8 and 9. In this case the strip **8** is folded over upon itself and is cemented together in close proximity to the slot **16** which is formed in the outer end thereof and is adapted to receive the indicating medium **18**.

As shown in Figs. 1 and 2, I have cemented, or otherwise secured, a relatively small piece of washable or waterproof paper **20**, to both of the strips **2** (as shown particularly in Fig. 2), but it will be understood that this piece of washable paper may or may not be used as on the form of marker which is described above.

40 In Fig. 10, I have shown a modified form of marker which is substantially the same in its general construction, but which is provided with strips **22** placed over the upper portion of the page **24** to be marked, and to which are cemented the laterally extending strips **26** which are provided with a protruding portion **28** on the outer edge thereof. Similar strips **30** are adapted to extend from the lower portion of the page **24** upwardly and are slidably secured to the strips **22** by the straps **32** which are secured to the strips **30** and extend around the strips **22**. These straps **32** may be pushed in an upward direction until the upper edges of the straps **32** are abutting against the lateral extending strip **26**. The strips **30** may be pulled downwardly until the lower edge of the straps **32** abut against the stops **34** which are cemented to the lower ends of the strips **22**. It will be understood that the strips **22** and **30** are telescopically connected, as shown more particularly in Fig. 13, and are adapted to fit one size page while the marker is in its contracted position and to fit varying larger sizes of pages as the telescopic strips are stretched outwardly as shown in dotted lines in Figs. 10 and 13.

65 In Fig. 16, I have shown an ordinary page **36** of a book on which five separate markers have been placed. These markers are made in varying shapes, as illustrated, so that the several markers may be placed on one page of the book and yet the protruding lateral marking strips **38** will not overlap and may be readily seen and selected by the person wishing to refer to the particular page which is marked. It will be understood that these several markers shown in Fig. 16 will be preferably made of a transparent material, so that

printed matter on the page **36** may be read without removing the several reference markers.

Markers shown in Fig. 16 are shown all applied to one page, but it will be understood that these markers of varying configuration may be used on different pages, so that the indicating means protruding beyond the edge of the pages will not overlap, and also so that the strips **40**, which are placed one on each side of a page being marked, will not all assume a position of the same relative distance from the binding of the book. These markers shown in Fig. 16 are, generally speaking, the same as the markers shown in Figs. 1 and 2, although the memoranda sheet **20** has been left off of the top of the markers so that more than one marker may be applied to one page without interfering in any way with the other markers applied to that same page.

By means of the varying configuration of these markers, a great many markers may be used in one volume without damaging the binding by expanding the covers too great a distance.

In the form which I have shown in Fig. 17, I have illustrated a telescoping form of marker similar to that shown in Fig. 10, which is provided with two laterally extending strips **42** which are secured to the holding strip **44**. This form of marker is adapted to hold a sheet of waterproof or washable paper **46** in position over a page **48** which is to be marked. The memoranda sheet **46** is held in position by the straps **50** which are cemented to the under side of the memoranda sheet **46** and form loops through which the laterally protruding strips **42** may pass to hold the memoranda sheet in position. These memoranda sheets **46** are adapted to be readily removable from the marker shown in Fig. 17 by merely sliding the memoranda sheet off over the ends of the laterally extending strips **42**.

While I have shown in Fig. 19, two of these memoranda sheets **46** positioned on opposite sides of a page **48** by being slipped into position over the laterally extending strips **42** on opposite sides of the page, it will be understood that the marker disclosed in Figs. 17, 18, 19, and 20 need not necessarily be provided with laterally extending strips **42** on both sides of the page **48** being marked.

This form of telescoping marker shown in Fig. 17 differs from the form shown in Fig. 10 in that the holding strips **44** extend from the top of the page **48** downwardly and are positioned over the strips **43** which extend upwardly from the bottom of the page **48**. At the bottom edges of the strips **43**, I provide binding straps **45** which are cemented to the strips **44**, and hold the strips **43** in position at the bottom of the strip **44**. At the upper end of the strips **43**, I provide stops **47** which are cemented to the strips **43** and are adapted to slide with the strips **43** between the strips **44**. After the strips **43** have been pulled through their entire length and the markers expanded to fit to the largest possible page to which it may be applied, the stops **47** abut against the straps **45** and preclude the marker from being enlarged more. This form of telescoping marker may be pushed into a smaller space than the form disclosed in Fig. 10, because the straps **45** are mounted at the bottom end of the marker and will remain in a fixed position relative to the laterally extending strips **42**, whereas in Fig. 10, the straps **32** slide on the strips **22** and abut against the laterally extending strip **26** when the marker is in its collapsed position.

Figs. 21 and 22 disclose a strip 8 which has been folded over upon itself, this being particularly adapted to be used at the lower end of the marker so that no portion of the marker will 5 extend beyond the bottom edge of a page, and thereby make it impossible or difficult to place a book in a standing position upon a book-shelf after one or more of my marking devices have been applied to the book.

10 It will be understood that the upper ends of the marker may be made in this form as well as the lower end, in which event one strip 8 will be folded over upon itself at two points, and the ends of the strip will be secured together at some 15 convenient place by any suitable means.

While I have shown several slightly modified forms which my bookmarker may take, it will be understood that other minor changes may become apparent from time to time as these modified 20 forms of markers are applied to varying types of books, card-digests and the like, to which they may be applied to afford easy reference to any selected passage, citation, or quotation.

I claim:

25 1. A set of bookmarkers for use on pages of a book, each bookmarker including a pair of relatively thin longitudinally extending strips secured together at at least one of their ends, said pair of strips adapted to straddle a book page to 30 be marked, and a pair of laterally extending strips secured together at their free ends and at their other ends secured to the first mentioned strips, said laterally extending strips of each bookmarker being of different length than the 35 laterally extending strips of each other bookmarker, and said laterally extending strips being secured to the longitudinally extending strips at varying points relative to the length of said longitudinally extending strips, whereby the said 40 strips of the marker for one page will not be superimposed upon the said strips of the marker for another page.

2. A set of book-markers for use on pages of a book, each marker including two pairs of strips 45 secured together, one pair secured together at both ends thereof and adapted to straddle a page of a book, the other pair being secured together at one of their ends and extending laterally from and secured to the first-mentioned pair 50 of strips between the ends thereof at their other ends, said pairs of strips adapted to straddle a

page to be marked, said laterally extending strips of one marker being of a different length from those of another so that one marker will not be superimposed upon another.

3. A set of book-markers for use on pages of 5 a book, each marker including one pair of strips secured together at both ends thereof and adapted to straddle a page of a book, and a second pair of strips secured to the first-mentioned pair of strips at one of their ends and said second pair 10 of strips secured together at their free ends, said second pair of strips of each marker differing in length from the length of a similar pair of strips of another marker, and the second pairs of strips being secured at different points on the 15 first-mentioned pairs of strips, whereby one marker will not be superimposed upon another when in place upon the pages of a book.

4. A bookmarker including a pair of relatively thin longitudinally extending strips, secured together at their ends and straddling a book page along the length thereof and a pair of laterally extending strips secured together at their free ends and to the longitudinally extending strips at their other ends, said laterally extending strips 20 straddling the book page along the width thereof, the free ends of the said lateral strips being adapted to engage the edge of the book page to 25 position the said longitudinally extending strips a predetermined distance from the binding of 30 the book.

5. A bookmarker including a pair of relatively thin longitudinally extending strips, secured together at at least one of their ends and straddling a book page along the length thereof, and 35 a pair of laterally extending strips secured together at their free ends and to the longitudinally extending strips at their other ends, said laterally extending strips straddling the book page along the width thereof.

6. A bookmarker including a pair of thin longitudinally extending extensible strips secured together at their outer ends, whereby they may be adjusted to the length of the page to straddle the latter along the length thereof, and a pair 40 of laterally extending strips secured together at their free ends and connected to the longitudinally extending strips at their other ends, said laterally extending strips straddling the book page along the width thereof.

CORNELIUS C. WASHBURN. 50
